(57) **CLAIM**

I claim the ornamental design for a bracelet with removable spray bottle, substantially as shown and described.

DESCRIPTION

FIG. 1 is a top, perspective view of the bracelet with removable spray bottle; the view showing my new design; FIG. 2 is a front elevation view thereof; FIG. 3 is a side elevation view thereof; FIG. 4 is a side elevation view thereof; FIG. 5 is a rear elevation view thereof; FIG. 6 is a top view thereof; FIG. 7 is a bottom view thereof; FIG. 8 is a top, perspective thereof; FIG. 9 is a top, perspective view thereof; the view showing the actuator in the open position; and, FIG. 10 is a top, perspective view thereof; the view showing the actuator in the open position; the view showing the spray bottle detached from the bracelet; the view showing an exploded view of the spray bottle portion.

A description of the appearance of the article is as follows: A bracelet with removable spray bottle.
